DESIGN FOR A ROSARY

Richard J. Lukeman, Montreal, Quebec, Canada

Application November 8, 1948, Serial No. 149,528
In Canada October 26, 1948

Term of patent 14 years

(Cl. D45—16)

To all whom it may concern:

Be it known that I, Richard J. Lukeman, a Canadian citizen, and resident of the city of Montreal, in the Province of Quebec, Dominion of Canada, have invented a new, original, and ornamental Design for a Rosary, of which the following is a specification, reference being had to the accompanying drawing, forming a part thereof.

In the accompanying drawing:

Figure 1 is a plan view of a rosary embodying my design.

Figure 2 is a perspective view of one of the units shown in Figure 1.

Figure 3 is a perspective view of the last three pendant units shown in Figure 1.

I claim:

The ornamental design for a rosary, as shown.

RICHARD J. LUKEMAN.
